HENRY M. CHANCE, OF PHILADELPHIA, PENNSYLVANIA.

METHOD AND APPARATUS FOR CENTRIFUGAL THICKENING OF MIXTURES AND CLARIFYING OF LIQUIDS.

Application filed July 29, 1925. Serial No. 46,752.

My invention relates to the thickening of ore pulps or other mixtures of liquid and comminuted solids and the partial or complete clarification of a portion of the liquid constituent of said pulp or mixture by centrifugal force or by centrifugal force and gravitation.

In centrifugal separators used for separating solids from mixtures of liquids and solids, for the clarification of the liquid of such mixtures and for similar purposes, in which separation is effected in a rotating vessel, the solids pack upon the inner walls of the separator, and are removed continuously by plows or scrapers usually rotating at slower speed than the separating vessel, or are periodically removed by cutting off the feed and removing the accumulation, with or without stopping or slowing down the separator. Centrifugal ore concentrators have been operated in a similar manner.

In the practice of my invention separation is effected in a stationary container, of any suitable shape, such as a tank of cylindrical or truncated cone type, the axis of which is preferably, but not necessarily, vertical, which is provided with a rotor or other means by which a rotary motion may be communicated to any fluid mixture introduced into the said container. The mixture to be thickened, preferably, but not necessarily, is introduced at or adjacent to the inner periphery of the container and acquires a rotary motion from energy transmitted by the rotor, the extreme outer periphery of which is spaced a suitable distance from the inner periphery of the container, the annular space thus provided being the locus in which thickening is effected of the coarser and heavier particles of solid matter, the finer particles being separated from a portion of the liquid with which they are admixed in the zone of highest rotating velocity, at or within the outer boundaries of the rotor.

Particles of solid matter thrown radially outwardly from the rotor by the centrifugal force of rotation, enter a zone adjacent to the walls of the container in which the velocity of rotation is reduced by friction with said walls, and thus having their velocity of rotation reduced, with corresponding reduction in centrifugal force, are free to fall by gravity to the lower part of the container, their downward paths of travel being a

curve approaching a helical or helical spiral type.

The solid material thus thickened by separation from a large portion of the liquid, upon reaching the base of the container may be continuously discharged through adjustably controlled outlets.

The clarified or partially clarified liquid occupies the space within the outer boundaries of the rotor, with the most highly clarified liquid in the central and upper portion of said space, from which it may be discharged continuously by gravity, centrifugal force, natural overflow or other means.

An outstanding feature of my invention, in its most efficient application, is the introduction of the mixture to be separated into the zone in which thickening is being effected, thereby preventing the clarified liquid occupying the central and upper zone from becoming admixed with mixture being fed into the separator. I do not confine myself to this mode of operation as the mixture may if desired be introduced through the center to the base of the rotor as is practiced in centrifugal separators in which the separating vessel is the rotating element. In the operation of my invention it is, however, essential that the interior of the rotor shall be in free communication with the annular space between the rotor and the walls of the container.

In the drawings Fig. I is a vertical cross-section and elevation of an apparatus in which my invention may be carried out. Fig. II is a cross-section at the line A—A of Fig. I showing the construction of the rotating element and its position with reference to the walls of the vessel. Fig. III is a construction similar to Fig. I but providing a different method for discharging the clarified liquid. Figures IV, V, VI and VII are cross-sections illustrating different types of rotor construction.

In Fig. I, a stationary container with a removable cover is shown by 1; this cover is extended upwardly as a feed conduit and hopper 2. A vertical rotating shaft 3 is shown mounted in bearings 4, 4^a, bearing 4 being provided with forced water lubrication controlled by valve 5. The shaft 3 is driven by a pulley 6, and is supported by a thrust ball bearing 7 which carries the weight of the shaft and of the rotor mounted

théreon. The rotor shown consists of a base 8, a cylindrical perforate shell 9, reinforcing hoops 10, and impelling and anti-diffusion vanes 11, which are spaced and held in position by spacing and anchorage rods 12, the upper part of rotor being braced to the shaft by collar and bars 13. Above the rotor, and mounted in fixed position within said container 1, is a distributing feed cone 14, to which are attached the valve controlled outlets 15, which furnish the means for discharging clarified liquid. This distributing cone 14 has a cylindrical downward extension which may be carried down to secure delivery of the mixture at any desired depth in the container 1. The thickened mixture is discharged through valve controlled outlets 16 at or adjacent to the base of the container 1.

20 The enlarged cross-section shown by Fig. II illustrates the construction of the rotor, and the relation of the diffusion vanes 11, perforate shell 9, spacing bars 12, and reinforcing hoops 10.

25 In Fig. III which duplicates many of the details shown by Fig. I, the rotating shaft 3' is a pipe or conduit which replaces the valved outlets 15 of Fig. I as a means for discharging the clarified liquid, the discharge through 3' being controlled by the movable sleeve 17 operated by the hand lever 19 which covers or uncovers the ports 18 shown at the base of the hollow shaft 3'. In this design the distributing feed cone 14' is connected to and becomes a part of the rotor and is provided with vertical radial vanes attached to its upper surface and running with small clearance below the under surface of the cover of the container 1'.

40 In both of the types illustrated by Figs. I and III, the feed conduit and hopper 2, 2' provides for operating the apparatus under any desired hydraulic head or pressure so that the apparatus is kept full of liquid and mixture, thus excluding air from the interior. It will however be apparent to those familiar with the operation of centrifugal separators of other types, that complete enclosure of the apparatus is not essential to successful functioning. In thickening mixtures of relatively coarse solids and liquid, where high rotative speed is not essential to successful performance, the opening in the top may be of relatively large diameter, the feed introduced through a central feed pipe discharging near the base of the rotor and the clarified liquid discharged by overflow at the opening in the top of the container 1. I therefore do not limit myself to the particular construction or arrangements of parts shown by the drawings, as many other known types of construction can be employed in carrying out my invention as herein described and claimed.

65 The construction of the rotor as shown by

Figs. I and III is a hollow cylindrical cage with perforate walls and closed bottom, or closed bottom and top, the interior being subdivided by vertical radial vanes. It will be understood that the interior of the rotor 70 may be subdivided by any suitable means into a series of channels radiating in straight or curved lines towards the periphery, an extreme type of such subdivision being a honey-comb structure, the object of such subdivision being to restrain the formation of eddy currents and counter-flow within the body of the rotor. The perforate shell 9 tends to restrain the development of irregular mass movements within the body of the 80 rotor. If a sufficient number of vanes are used to restrain such movements, the perforate shell 9 may be eliminated as a structural part of the rotor.

Fig. IV is a cross-section of a portion of 85 a rotor illustrating a construction with annular diaphragms 21, which may be perforate as shown, which may be inclined or horizontal, and may be used with or without intersecting vertical vanes similar to 90 those shown by 11 of Fig. I. This drawing also illustrates the use of an inner perforate shell 9a. Attachment to the shaft 3 is illustrated by the arms and collar 13a.

Figures V, VI and VII illustrate the subdivision of the space within the rotor by a cellular structure shown as of the honey-comb type, each cell diminishing in height from the outer to the inner periphery of the rotor. It will be understood that the centrifugal force will prevent the cells from becoming clogged with sediments when this type of construction is employed. The cells 100 at the larger end are shown by enlarged end view Fig. VI and at the smaller end by 105 enlarged end view Fig. VII. The cells may be horizontal or inclined.

The container may be of any suitable form, preferably of cylindrical, truncated cone or barrel shaped type.

110 The rotor should be adapted to impart rotary motion to that portion of the mixture or liquid in which it is immersed, with minimum disturbance of that portion of the liquid in the annular clearance space between the periphery of the rotor and the wall of the container, and with minimum production of eddy currents, circulatory flow or mass movements in the mixture or liquid within the body of the rotor, while permitting free flow or movement of said liquid or mixture towards or away from the periphery or the center of said rotor, said freedom of movement preferably, but not necessarily, being in a radial direction. To 115 insure such free flow or movement of liquid or mixture through the rotor and thus provide the essential free communication between the interior of the rotor and the space external to the rotor, the perforations in 120

shells 9 of Figs. I and II, of 9' of Fig. III, of 9 and 9^a of Fig. IV, or of diaphragms such as 21 of Fig. IV, must be large enough to freely pass the largest particles of the 5 comminuted solids; such perforate shells, diaphragms or the like, being designed for use solely in restraining the formation of eddy currents and erratic mass movements of the fluid mixture, or of the fluid, and are 10 therefore not utilized or utilizable for screening or filtering. Restraint of objectionable movements within the body of the rotor may be effected by vanes, diaphragms or partitions of relatively thin material confining 15 the flow of mixture or liquid within channels of relatively small cross-sectional area. This will be readily understood by those familiar with centrifugal separators in which both the container and the impelling 20 vanes rotate as a unit.

My invention may be carried out by utilizing a centrifugal separator, of the types in common use for separating cream or butterfat from milk, as the rotor, and installing 25 this in a stationary container of the types illustrated by Figs. I and III, first removing, by perforations, or otherwise, sufficient portions of the wall of the separator to permit material tending to bank upon said wall 30 to freely pass from the rotor into the annular space between the rotor and the said stationary container.

Having described my invention, I claim—

1. In separating a fluid mixture of liquid 35 and comminuted solids heavier than said liquid into a clarified or partly clarified liquid and a thickened mixture of said liquid and solids, the improved method which consists in imparting substantially uniform angular speed of rotation to a substantially vertical cylindrical body of said fluid mixture; in introducing said mixture to be separated into

a region of high rotative speed at a point exterior to but closely adjacent to the peripheral boundary of said rotating body; 45 in causing said solids, by centrifugal force to move away from the center of rotation towards and into a region of relatively slow rotation beyond the peripheral boundary of said rotating body; in causing the said liquid 50 to move towards the center of rotation, whereby the said liquid is clarified and the said mixture is thickened, and in removing said liquid from the said central region of rotation and the said thickened mixture from 55 said peripheral region.

2. A centrifugal separator comprising in combination a rotor mounted upon a shaft equipped with bearings and means for imparting rotary motion to said shaft, said rotor including a base and a perforate outer wall with perforations larger than the particles of solid matter to be separated by said separator, the region of said rotor adjacent to said shaft being in free communication 60 with the region of said rotor adjacent to the inner surface of said perforate wall through channels materially larger than the said particles; a container with walls substantially 65 concentric to said rotor in which said rotor is mounted; a clearance space of substantial 70 width between the outer wall of said rotor and the inner wall of said container; means for feeding the materials to be separated directly into said clearance space exterior to 75 said rotor; means for removing clarified liquid from said region adjacent to said shaft and means for removing thickened material 80 from the region adjacent to the inner wall of said container.

Signed at Philadelphia, Pa., this 23d day of July, 1925.

HENRY M. CHANCE.
